(57) **CLAIM**

The ornamental design for a microscope assembly, as shown and described.

DESCRIPTION

FIG. 1 is a perspective view of the microscope assembly of my new design;

FIG. 2 is a rear elevation view of said microscope assembly of FIG. 1;

FIG. 3 is a left side elevation view of said microscope assembly of FIG. 1;

FIG. 4 is a bottom plan view of said microscope assembly of FIG. 1;

FIG. 5 is a front elevation view of said microscope assembly of FIG. 1;

FIG. 6 is a right side elevation view of said microscope assembly of FIG. 1; and,

FIG. 7 is a top plan view of said microscope assembly of FIG. 1.

FIG. 8 is a perspective view of a second embodiment of the microscope assembly of my new design;

FIG. 9 is a rear elevation view of said microscope assembly of FIG. 8;

FIG. 10 is a left side elevation view of said microscope assembly of FIG. 8;

FIG. 11 is a bottom plan view of said microscope assembly of FIG. 8;

FIG. 12 is a front elevation view of said microscope assembly of FIG. 8;

FIG. 13 is a right side elevation view of said microscope assembly of FIG. 8; and,

FIG. 14 is a top plan view of said microscope assembly of FIG. 8.

The broken lines from no part of the claimed design.
